UNITED STATES PATENT OFFICE.

ROBERT PAUL STOUT, OF BETHLEHEM, NORTHAMPTON COUNTY, AND WILLIAM L. LUKENS, OF BETHLEHEM, LEHIGH COUNTY, PENNSYLVANIA, ASSIGNORS TO THE BETHLEHEM STEEL COMPANY, OF SOUTH BETHLEHEM, PENNSYLVANIA, A CORPORATION OF PENNSYLVANIA.

FUSE FOR EXPLOSIVE PROJECTILES.

1,145,937.

Specification of Letters Patent. Patented July 13, 1915.

Application filed December 7, 1914. Serial No. 875,970.

To all whom it may concern:

Be it known that we, ROBERT PAUL STOUT and WILLIAM LESLIE LUKENS, citizens of the United States, residing at Bethlehem, Northampton county, and Bethlehem, Lehigh county, State of Pennsylvania, respectively, have invented certain new and useful Improvements in Fuses for Explosive Projectiles, of which the following is a 10 specification.

This invention relates to fuses for projectiles and has for one of its objects the provision of a fuse which is normally unarmed and perfectly safe and proof against 15 premature explosion due to dropping or roughly handling.

Another object of the invention is to provide a fuse which, while normally in an unarmed condition, is automatically armed 20 when the projectile is in flight and so constructed as to be thoroughly reliable in operation.

Other objects and the features of novelty will be apparent from the following description, taken in connection with the accompanying drawings, in which,

Figure 1 is a longitudinal section of a fuse embodying the invention, the parts being shown in the unarmed position; Fig. 2 is a 30 view similar to Fig. 1 but showing the parts in the armed position; Fig. 3 is a section on the line 3-3 of Fig. 1; and Fig. 4 is a section on the line 4-4 of Fig. 1.

Referring to the drawings, 10 indicates 35 the usual shell or body member of the fuse which is provided with the external threads 11 by means of which the fuse is secured in position in the projectile. The body member 10 is provided with a chamber 12 in which 40 a hammer 13 is slidably arranged. The inner end of the body member has secured therein a cap 14 containing an exploding charge 15 and a percussion primer 16. The parts 10, 14, 15 and 16 may be of any preferred construction.

The hammer 13 comprises an outer shell into which a block 17 is secured by pins or any preferred method, this block having an axially arranged chamber 18 in which there 50 is a firing device 19. The device 19 is essentially a pin having a point 20 and spaced collars 21. The block 17 is provided with

two or more radial openings 22 in which are arranged the centrifugal weights 23. Springs 24 enter the outer ends of the 55 weights 23 and normally press these weights against the firing device 19. As shown in Fig. 1, the weights 23 have their inner ends normally arranged between the collars 21 of the firing device and thus hold this device in 60 the unarmed position against the action of the spring 25. From Fig. 1 it will be evident that with the firing device 19 in the position shown, it will be impossible for the point 20 to strike the primer 16 even if the 65 fuse were dropped, and struck on the cap 14 thereby causing the hammer to compress the spring 26 which normally holds the hammer in the end of the chamber 12 remote 70 from the primer. The point 20 of the firing device is, in the unarmed position, within the hammer, so that the end of the hammer would strike the inner surface of the cap 14 before the point 20 could possibly strike the 75 primer 16.

At the end of the chamber 18 is an abutment 27, which, as shown in Fig. 2, limits the arming movement of the firing device 19 and when the firing device is in this position the point 20 projects from the forward end of 80 the hammer and is in position to strike the primer 16 when the hammer moves toward the cap 14. At the rear of the block 17 is a chamber 28 in which is a disk 29 having an eccentrically arranged perforation 30 85 through which the end of the firing device 19 projects when the fuse is in the unarmed position, as shown in Fig. 1. With the parts in this position the disk 29 is held against lateral movement by the firing device but 90 when the latter moves into the armed position shown in Fig. 2 the disk is released and permitted to move laterally to carry the perforation 30 out of alignment with the firing device and thus prevent a return 95 movement of the latter to the unarmed position. With the parts in the position shown in Fig. 2 it will be evident that the disk 29 forms an unyielding connection between the hammer and the end of the firing device and 100 also locks the firing device against the abutment 27. The firing device is therefore, in the armed position, rigidly connected with the hammer and thus when the flight of the

projectile is interrupted the full force of the hammer will be transmitted to the firing device to drive the latter into the primer.

The operation of the fuse is as follows:

- 5 When the fuse is applied to the projectile the parts are in the position shown in Fig. 1 and the projectile may be handled with perfect safety. When the projectile is fired from the gun the rotation causes the weights 10 23 to be thrown out radially against the action of the springs 24. This releases the firing device 19 and permits the spring 25 to move the device forwardly into the position against abutment 27 as shown in Fig. 2. In 15 this position the weights 23 are prevented from returning to their former position by one of the collars 21 and, in case the rotation of the projectile were wholly or partially interrupted, the fuse would still remain in the 20 armed position. The disk 29, having been released by the forward movement of the firing device, assumes the position shown in Fig. 2 on account of the centrifugal force 25 acting on this disk and thus forms a positive connection between the firing device and the hammer. When the projectile strikes, the inertia of the hammer causes it to move forward and force the point 20 of the firing device into the primer so as to explode the latter.

It will be evident that changes may be made in the details of construction without departing from the spirit of our invention and we therefore do not wish to be limited 35 to the exact details and arrangement shown in the drawings.

Having thus described the invention what is claimed and desired to be secured by Letters Patent is:

40 1. In a fuse for projectiles, the combination of a firing device, automatically unlocked means for normally restraining said device from arming movement, a hammer, spring means for moving said device into armed position, and means whereby said device is locked in the armed position.

2. In a fuse for projectiles, the combination of a firing device, automatically unlocked means for normally restraining said 50 device from arming movement, a hammer, spring means for moving said device into armed position, and means for forming an unyielding connection between said device and the hammer when the former is in the 55 armed position.

3. In a fuse for projectiles, the combination of a firing device, automatically unlocked means for normally restraining said device from arming movement, a hammer, 60 spring means for moving said device into armed position, and means carried by said hammer for locking said device in the armed position.

4. In a fuse for projectiles, the combination of a firing device, automatically un-

locked means for normally restraining said device from arming movement, a hammer, spring means for moving said device into armed position, and a centrifugal element for automatically locking said device in the 70 armed position.

5. In a fuse for projectiles, the combination of a firing device, automatically unlocked means for normally restraining said device from arming movement, a hammer, 75 spring means for moving said device into armed position, and a centrifugal element normally held by said device and adapted, when released, to move to a position in which it forms an unyielding connection between 80 the device and said hammer.

6. In a fuse for projectiles, the combination of a hammer, a firing device carried by the hammer and movable relatively thereto, automatically unlocked means for normally restraining said device from arming movement, spring means for moving said device into the armed position, and means for positively locking said device to the hammer in the armed position.

7. In a fuse for projectiles, the combination of a hammer, a firing device carried by the hammer and movable relatively thereto, automatically unlocked means for normally restraining said device from arming movement, spring means for moving said device into the armed position, and a centrifugal element for automatically locking said device in the armed position.

8. In a fuse for projectiles, the combination of a hammer, a firing device carried by said hammer and movable relatively thereto, one or more centrifugal elements carried by the hammer and normally restraining said device from arming movement, spring means 105 for moving said device into the armed position, and means whereby said device is locked in the armed position.

9. In a fuse for projectiles, the combination of a hammer, a firing device carried by said hammer and movable relatively thereto, an abutment on said hammer for limiting the arming movement of said device, one or more centrifugal elements carried by said hammer and normally restraining said device from arming movement, means for automatically moving said device into the armed position, and an automatically actuated element normally restrained by said device and movable when the latter is in the armed position to lock the device to said hammer.

10. In a fuse for projectiles, the combination of a body member, a primer carried thereby, a hammer arranged in said body member, spring means for normally holding said hammer away from said primer, a firing device adapted to be driven against said primer by said hammer, automatically unlocked means for normally holding said de-

vice in the unarmed position, spring means for moving said device into the armed position, and means forming an unyielding connection between said device and the hammer when the former is in the armed position.

11. In a fuse for projectiles, the combination of a body member, a primer carried by said body member, a hammer arranged within the body member, spring means for holding said hammer away from said primer, a firing device carried by said hammer and movable therein, automatically unlocked means for normally holding said device in the unarmed position, spring means for moving said device into the armed position, and means carried by the hammer for locking said device in the armed position.

12. In a fuse for projectiles, the combina-

tion of a hammer having an axial opening therein, a firing device arranged in said opening; means for holding said device in the unarmed position, spring means for moving said device into the armed position, and a laterally movable member carried by the hammer and adapted to assume a position in the rear of said device, when the latter is in the armed position, and form an unyielding connection between the hammer and said device.

In testimony whereof we affix our signatures in presence of two witnesses.

ROBERT PAUL STOUT.
